CLOSURE

Merrill L. Rathbun, Salamanca, N. Y.

Application January 12, 1940, Serial No. 313,551

2 Claims. (Cl. 206—44)

This invention relates to an improvement in pivotal structures for closures.

In one form the invention is applied to a closed receptacle such as may be used to package and display articles of jewelry. The receptacle shown comprises a body and cover. Two end pivots carried by the body serve to support the cover for rotation into or out of closed position.

The invention, although applicable in its present or modified form to other structures than the receptacle shown, is well adapted for use with molded receptacles. It will be understood, however, that the material from which the receptacle is formed has no bearing on the invention inasmuch as all moldable substances of which closed receptacles are made, as well as wood or metal, may be used.

One of the objects of the invention lies in the provision of improved pivotal means for relatively rotatable members.

Another object of the invention lies in the provision of pivotal means for a closed receptacle that is carried by the body thereof and serves to support a closure for rotation into or out of closed position.

Another object of the invention lies in the provision of pivotal means for the closure of a receptacle that is spring mounted in the body portion thereof.

Another object of the invention lies in the provision of pivotal means for the closure of a receptacle that is self-positioning and securing in the body of the receptacle.

Another object of the invention lies in the provision of pivots for a closed receptacle that are sturdy and are adaptable in different sizes for the requirements of closed receptacles of various sizes.

Another object of the invention lies in the provision of pivots for the closure of a receptacle that, when in position of use, are entirely concealed both from the interior and the exterior of the receptacle.

Other objects and advantages of the invention will be more fully understood from a consideration of the following specification taken in conjunction with the accompanying drawing; and in which

Figure 1 is a perspective view of one form of closed receptacle shown in open position, embodying the invention;

Figure 2 is a front elevational view of the receptacle in closed position, parts being broken away to disclose the location and mounting of one of the pivots;

Figure 3 is a transverse vertical sectional view taken substantially on the line 3—3 of Figure 2;

Figure 4 is a vertical sectional view, similar to that of Figure 3, showing the closure in fully opened position; and

Figure 5 is a partial front elevational and sectional view of the elements of the receptacle and pivots prior to assembly.

Reference is now had to the drawing wherein the numeral 10 is employed to generally designate a closed receptacle with which one modification of the present invention may be employed. The receptacle comprises a body 11 and cover 12. The elements of the receptacle may be of any configuration and material. In the present instance the receptacle is of a type useful in packaging and displaying small articles of jewelry. The size of the receptacle, however, has no particular bearing on the applicability of the pivots thereto.

The receptacle 10 comprises rounded upright end walls 13, at the top of which are inwardly offset walls 14 that are continuations of the walls 13. The inner face of each wall 14 extends downwardly to form end walls 15 of that portion of the body that encloses articles to be packaged and displayed. Connecting the end walls 15 is an arcuate base wall 16. Formed in the end walls 15 are vertical slots 17 that extend from adjacent the top of said walls to the bottom edge of the base wall 16. Shallow recesses 18 in the base wall 16 connect with the slots 17. The forward edge of the base wall 16 terminates in a front wall 19 that, in the present instance, is inclined outwardly and ornamented by the provision of a ledge 20 and rounded relief portions 21. As may be readily understood from Figures 1 and 2 of the drawing, the end walls 13 are curved and blend with the relief portions 21 of the front wall 19.

The rear wall 22 of the body 11 is vertical and the rear edge of the base wall 16 blends therewith, substantially as indicated in Figure 3 of the drawing. The upper edge 23 of the base wall is of substantially the same height as the walls 14. Inasmuch as the body 11 is a molded article, no base other than the base 16 is necessary and the walls described are hollow for the purpose of decreasing both weight and cost of material.

The cover 12 is a semi-cylindrical member having a front tab or tongue 24 that may be inclined contrary to the curvature of the cover, substantially as indicated in the drawing. The sides of the tongue are cut away through an arc indicated at 25. This arc corresponds to the

curved surface of the relief portions 21 and when the cover is in closed position (see Figure 2) these parts interfit. In the outer faces of the vertical end walls 26 and adjacent their lower edges are small recesses 27.

The pivot members 28 serve to pivotally mount the cover 12 on the body 11. These pivot members may be formed from spring metal and each includes a strap-like body portion 29 that terminates at one end in a near right angle flange 30. The other end of the body portion terminates in a laterally directed pin 31 having a small flange 32 extending in the opposite direction. The pin 31 and flange 30 project in the same direction.

The cover 12 may be set into the body 11 with the parts in the position shown in Figure 4, that is, with the shoulder 33 of the tongue 24 resting on the upper edge 23 of the rear wall 22. With the cover in this position the recesses 27 register with the upper ends of slots 15. The pivot members may now be inserted from the under open side of the body 11. The members are moved upwardly to a point where the flanges 32 engage the rounded under surfaces 34 of walls 14. Contact of the flanges 32 with these walls project pins 31 through the upper ends of the slots into recesses 27. The lower flange 30 of each member is moved upwardly to project into the recess 18. To do this the body portion 29 of the pivot member must be slightly sprung, but it immediately returns to shape. It will be understood that the downward pressure of flange 30 in recess 18 and lateral and upward pressure of flange 32 holds the pin 31 in position in the recess 27. The cover is thus pivotally mounted in the body and prevented inadvertent displacement, since the only access to the pivot members is along the body portion 29 and this portion lies within the slot 15.

Although applicant has shown and described only one modification of pivot means for a closed receptacle, it will be understood by those skilled in the art that changes in shape and size of the receptacle, as well as in the pivot means, are contemplated insofar as such changes are within the spirit and scope of the invention as defined in the hereunto annexed claims.

Having thus set forth my invention what I claim as new and for which I desire protection by Letters Patent is:

10. A receptacle comprising a body and cover, said body having aligned slots in opposite interior walls thereof, said cover including opposed walls projecting into and in part overlapping the interior walls of said body, seats in said body at corresponding ends of said slots, resilient members having pivot portions engageable with the opposed walls of said cover, means on said members adjacent said pivot portions engageable with said body, and flanges on said members engageable with said seats, said members being sprung out of normal shape to facilitate seating said flanges following engagement of said means with said body, whereby said members, in operative position, will lie wholly within said slots.
15. A receptacle comprising a body and cover, said body having aligned slots in opposite interior walls thereof, said cover including opposed walls projecting into and in part overlapping the interior walls of said body, seats in said body at opposite ends of said slots, resilient members having pivot portions engageable with the opposed walls of said cover, the ends of said members being engageable with said seats, the relationship of the length of said members to said slots being such as to require springing said members out of normal shape to insert the ends thereof in said seats and locate said members wholly within said slots.
20. A receptacle comprising a body and cover, said body having aligned slots in opposite interior walls thereof, said cover including opposed walls projecting into and in part overlapping the interior walls of said body, seats in said body at opposite ends of said slots, resilient members having pivot portions engageable with the opposed walls of said cover, means on said members adjacent said pivot portions engageable with said body, and flanges on said members engageable with said seats, said members being sprung out of normal shape to facilitate seating said flanges following engagement of said means with said body, whereby said members, in operative position, will lie wholly within said slots.
25. A receptacle comprising a body and cover, said body having aligned slots in opposite interior walls thereof, said cover including opposed walls projecting into and in part overlapping the interior walls of said body, seats in said body at opposite ends of said slots, resilient members having pivot portions engageable with the opposed walls of said cover, the ends of said members being engageable with said seats, the relationship of the length of said members to said slots being such as to require springing said members out of normal shape to insert the ends thereof in said seats and locate said members wholly within said slots.
30. A receptacle comprising a body and cover, said body having aligned slots in opposite interior walls thereof, said cover including opposed walls projecting into and in part overlapping the interior walls of said body, seats in said body at opposite ends of said slots, resilient members having pivot portions engageable with the opposed walls of said cover, the ends of said members being engageable with said seats, the relationship of the length of said members to said slots being such as to require springing said members out of normal shape to insert the ends thereof in said seats and locate said members wholly within said slots.
35. A receptacle comprising a body and cover, said body having aligned slots in opposite interior walls thereof, said cover including opposed walls projecting into and in part overlapping the interior walls of said body, seats in said body at opposite ends of said slots, resilient members having pivot portions engageable with the opposed walls of said cover, the ends of said members being engageable with said seats, the relationship of the length of said members to said slots being such as to require springing said members out of normal shape to insert the ends thereof in said seats and locate said members wholly within said slots.
40. A receptacle comprising a body and cover, said body having aligned slots in opposite interior walls thereof, said cover including opposed walls projecting into and in part overlapping the interior walls of said body, seats in said body at opposite ends of said slots, resilient members having pivot portions engageable with the opposed walls of said cover, the ends of said members being engageable with said seats, the relationship of the length of said members to said slots being such as to require springing said members out of normal shape to insert the ends thereof in said seats and locate said members wholly within said slots.

MERRILL L. RATHBUN.
